Primary Examiner—Lucy Lieberman(74) *Attorney, Agent, or Firm*—Carnody & Torrance LLP(57) **CLAIM**

The ornamental design for a watch casing and portion of a strap, as shown and described.

DESCRIPTION

FIG. 1 is a perspective view of a watch casing and portion of a strap showing my new design;

FIG. 2 is a top plan view thereof;

FIG. 3 is a bottom plan view thereof;

FIG. 4 is a first end elevational view thereof;

FIG. 5 is a second end elevational view thereof;

FIG. 6 is a left side elevation thereof; and,

FIG. 7 is a right side elevational view thereof.

The dotted lines are intended to show features that are environmental only and form no part of the claimed design.
